ATTORNEY

WITNESS:

P. J. Snapp

UNITED STATES PATENT OFFICE.

JOHN PEMBERTON SNAPP, OF LIMESTONE, TENNESSEE.

CLINCHING TOOL.

Application filed May 7, 1926. Serial No. 107,484.

The object of this invention is to provide a tool for use in connection with the operation of splicing poles, such as telegraph and telephone poles when the upper pole section 5 is to be connected with that portion embedded in the ground.

A further object is to provide a tool adapted to secure the ends of the wire clamp employed in splicing the pole sections, and a 10 tool adapted to secure a tie member of wire which connects oppositely located portions of a clamp having loop form and extending around both pole sections.

A further object is to provide a device including an element having a plurality of hook members for engaging the pole clamp, and an element adjustable with reference to that first named and carrying an engaging device adapted to operate upon a tie member 20 extending transversely of the wire clamp.

A further object is to bend one end of said tie member around one side portion of the clamp, the other end having been passed between the pole sections and having been 25 connected with the opposite side of the clamp, incident to the manufacture of the device.

With the foregoing and other objects in view, the invention consists in the novel construction and arrangement of elements described, illustrated and claimed, it being understood that modifications may be made within the scope of the claims without departing from the spirit of the invention.

35 In the drawings forming part of this application;

Figure 1 is a view showing the pole clamp in top plan, and the pole sections to be spliced being illustrated in horizontal section, the 40 tool also being in top plan.

Figure 2 is a section longitudinally of sleeve 28 of Figure 1, the position of the tool being that assumed at the beginning of the operation of connecting the tie member 45 of Figure 1 with the clamp.

Figure 3 is a view showing the position of the tool at the next stage of the operation, the end of the tie wire having been bent at approximately a right angle with reference 50 to the main portion of the tie member.

Figure 4 is a view showing the tool in the

next stage of the operation, and showing in dotted lines the position of the end of the tie member after it has been forced over to clinching or final position. 55

Figure 5 is a detail view in section, longitudinally of the tool.

Figure 6 is a section on line 6—6 of Figure 5.

Figure 7 shows the outer end of the lever 60 or handle of Figure 1, in longitudinal section, this element being tubular, so that it may be applied to one end portion of the clamp after the latter has passed thru the eye portion referred to below. 65

Figure 8 is a detail view showing the use of the outer end of the lever or handle under other conditions, a transverse bore thru the lever having been applied to the end of the clamp for the purpose of bending said 70 end to the position desired for clinching the end of the clamp after it has passed thru the eye member.

Figure 9 is a detail view showing the end 75 of hook element 34 of Figure 1 and elsewhere.

Figure 10 shows the application of the tool to the clamp, in position for bending the tie member downwardly with reference to the clamp. 80

Figure 11 is a detail view showing the clinched ends of the wire clamp.

The sections of the pole to be spliced are designated 10 and 11 and the wire clamp is shown at 12, and is adapted to extend 85 around both sections 10 and 11, one end of the wire clamp having an eye member 14 formed thereon, and a spike 15 extending from the eye member and adapted to enter the pole section 11. 90

A transverse tie member 17 is connected in any suitable manner with the wire clamp, at the point 18, this connection usually being made by bending the tie around the clamp when the latter is formed at the factory. 95

In order to clinch the end portion 19 of clamp 12, after the latter has passed thru the eye member 14, I employ a tubular lever 20, the longitudinal bore of which is designated 21, a transverse bore being shown at 22. Either bore 21 or 22 may be employed 100

for the purpose of clinching or bending the extreme end of the wire clamp after passing thru the eye. In Figure 8 the projecting end portion 19 is engaged by the transverse bore 22 in order to perform the bending operation indicated, and in Figure 7 the longitudinal bore 21 is employed, these two operations being provided for in order that the tubular lever 20 may be employed as proves to be most convenient under any given circumstances.

The opposite end of lever 20 carries a special element or elements adapted for connecting tie member 17 with the clamp 12, at the point shown in Figure 1. The end portion of lever 20 opposite that provided with bore 22 is threaded as shown at 25, and a sleeve or the like designated 26 is movable longitudinally of the threaded portion of lever 20, the threads being on opposite edge portions as shown especially in Figures 1 and 6, and the remaining portions of this part of the lever being flat as shown at 27.

A cutaway portion in sleeve 26 accommodates an internally threaded sleeve or nut 28, this element last named surrounding the threaded portion of lever 20, and the elements just referred to operating on the principle of a common form of wrench.

Connected with the sleeve 26 are prongs such as 30, the latter terminating in hook portions 31 adapted to surround the wire clamp 12, or partly surround the latter in the manner illustrated in several of the views. In view of the adjustable mounting specified, the forked and hooked device is movable longitudinally of lever 20, for the purpose of varying the distance between the hooks 31 and the tie engaging member 33.

The end of lever 20 carrying the tie engaging member 33 projects beyond the hooks 31 to the extent determined by the position of the adjusting member 28, and the extreme end 34 of element 33 extends over the tie member 17, so that positive engagement therewith is effected. The hooks 31 are in engagement with clamp 12, in the manner shown in several of the views, and lever 20 is then turned from an approximately horizontal position, or position in the plane of the wire clamp 12 to a position approximately perpendicular with reference thereto. The tool is now released and again applied in the position of Figure 4, and the projecting end of the tie member 17 is forced to the dotted line and clinching position illustrated in that view, the complete operation being effected within a very brief space of time, and the opposite sides of the wire clamp 12 being thereby positively connected, the tie 17 extending between the pole sections 10 and 11. It is obvious that the tool may be employed for clinching the tie member, without regard to the special

form of wire clamp provided, it only being essential that the clamp include elements extending with reference to the pole sections, in the manner illustrated in Figure 1,—the object being to produce any required degree of tension on the sides of the loop member comprising the clamp.

Having described the invention what is claimed is:

1. In a device of the class described, a handle member, a hooked element adjustably mounted for longitudinal movement on the handle, clamp-engaging means carried by said element, and a device extending from the end of the handle, longitudinally thereof and beyond the end of the clamp engaging means, and adapted to engage and bend a tie around the clamp, by movement of the handle angularly with reference to said clamp. 75
2. In a device of the class described, a handle member, an element carried by the handle and including spaced clamp-engaging means, and a device extending from the handle and between the spaced means and transversely of the direction in which the handle is moved in operation, this transverse device being adapted to engage and bend a tie around said clamp. 80
3. In a device of the class described, a handle member, an element adjustably mounted for longitudinal movement on the handle, hooked and forked clamp-engaging means carried by said element, and a device extending from the end of the handle beyond the outer end of the clamp engaging means, and adapted to engage and bend a tie around the clamp, by movement of the handle angularly with reference to said clamp. 85
4. In a device of the class described, a handle member, an element mounted on the handle, forked clamp-engaging means carried by said element, a device carried by the end of the handle and between the forked means and adapted to engage a tie member extending transversely of the clamp and to bend the tie around the clamp, and adjustable means for varying the relative position of the forked means and the device carried by the end of the handle. 90
5. In a device of the class described, a handle and an offset tie-engaging device carried by one end of the handle, the end of the tie engaging device projecting transversely of the handle, and clamp-engaging means carried by the handle on opposite sides of the tie engaging device, of decreased length compared therewith and adapted to partly surround a wire clamp when the tie-engaging device is in contact with a tie extending transversely of the clamp. 100
6. In a device of the class described, a handle member, an element mounted on the handle, forked clamp-engaging means car- 105

ried by said element, a device carried by the end of the handle and between the forked means and adapted to engage a tie member extending transversely of the clamp and to 5 bend the tie around the clamp, and adjustable means for varying the relative position of the forked means and the device carried

by the end of the handle, said adjustable means including a threaded device carried by the element mounted on the handle, and 10 the handle being threaded for cooperation with the threaded device first named.

In testimony whereof I affix my signature.

JOHN PEMBERTON SNAPP.
